TROUSER HANGER

Filed Sept. 6, 1943

This is a continuation-in-part of my application for a patent, filed on January 12, 1943, Serial No. 501,361, for a trouser hanger, and the present application relates to the improvement of the structure of the hanger as shown in Fig. 1 of the drawings.

The hanger is shown in a front elevational view in Fig. 1, and a vertical sectional view taken on line 2-2 of Fig. 1 in Fig. 2. Fig. 3 is an end view of the hanger with the trouser clamping members in open position; Fig. 4 is a top plan view of the hanger; Fig. 5 is a fragmentary end view of a modified form of hanger construction of my invention to be hereinafter described; and Fig. 6 is a front view with parts broken away of the modified structure shown in Fig. 5.

UNITED STATES PATENT OFFICE

2,382,459

TROUSER HANGER

Robert H. Wollin, Milwaukee, Wis., assignor to Wollin, Inc., Milwaukee, Wis., a corporation of Wisconsin

Application September 6, 1943, Serial No. 501,361

3 Claims. (Cl. 223—96)

This invention relates to improvements in trouser hangers.

The principal object and purpose of my invention is to provide a trouser hanger having very little metal in its construction thereby enabling the hanger to be made almost entirely of wood or other inexpensive non-metallic material, yet be sufficiently sturdy and strong to clamp a garment for hanging it in a dependent position in a closet, wardrobe or the like.

A further object of my invention is to provide the hanger with a pair of trouser or garment clamping members hingedly connected together for relative movement towards and from each other for opening and closing the hanger and having a locking element on one member and movable into engagement with the other member adjacent the hinge means for locking the members in their garment clamping or closed positions.

A further object of my invention is to provide the locking element in the form of a lever pivotally mounted on the member which supports it and swingable into and out of engagement with the other member for clamping and releasing a garment.

A further object of my invention is to provide the locking lever with an inclined end portion to co-act with the adjacent end of the other member for increasing the clamping pressure when clamping a garment in the hanger.

The invention consists further in the structural features hereinafter described and claimed.

In the accompanying drawing—

Fig. 1 is a front elevational view of a trouser hanger constructed in accordance with my invention, one of the trouser clamping members being partly broken away for the sake of illustration;

Fig. 2 is a vertical sectional view taken on line 2-2 of Fig. 1;

Fig. 3 is an end view of the hanger with the trouser clamping members in open position;

Fig. 4 is a top plan view of the hanger;

Fig. 5 is a fragmentary end view of a modified form of hanger construction of my invention to be hereinafter described; and

Fig. 6 is a front view with parts broken away of the modified structure shown in Fig. 5.

As shown in the drawing, the trouser hanger of my invention comprises a pair of trouser clamping members 1, 2 hingedly connected together by a hinge means 3 for the relative movement of the members towards and from each other for opening and closing the hanger. Said

members 1, 2 are in substantially flat, one-piece form fashioned of the desired inexpensive material preferably from ply-wood stock. This renders the hanger relatively light for ease in handling and sufficiently strong and rigid to withstand breakage and warping and tightly clamp the garment for suspension in a hanging or dependent position.

The members 1, 2 have straight integral jaw portions 4, 4 along the bottom of the hanger and long enough to fully extend across the lower or cuffed-ends of a pair of trousers to be clamped and hung up in a closet, wardrobe or the like by the hanger. The jaw portions 4 are fitted at their opposite ends with opposed felt pieces 5, 5 to hold the garment against slippage in the hanger and to prevent the clamping pressure marring the garment material.

The members 1, 2 are provided intermediate the ends of the jaw portions 4 with centrally upwardly extending rigid portions 6, 7 substantially alike and mounting therebetween the hinge means 3. The latter in the form shown in Figs. 1 to 4 comprises a number of staple-like fasteners 8, 8 inserted into each of the rigid portions 6, 7 from their opposed surfaces and a hinge pin 9 engaged in the loops of the fasteners. The opposite ends of the hinge pin 9 are respectively headed and spread to hold the pin in place. The hinge means is sufficiently spaced from the bottom of the hanger to give a wide spread to the members 1, 2 when opened to accommodate the hanger for garments of different thicknesses of material.

The rigid portions 6, 7 of the hanger members 1, 2 extend above the hinge means 3 to provide a space between the members when closed to receive the locking end 10 of a locking member 11 mounted on the member 1. The locking member 11 is in the form of a lever pivoted by a pivot pin 12 on the hanger member 1 above the upper end of the member 2. The locking end 10 of the lever 11 fills the space between the members 1, 2 above the hinge and holds said members in their closed or clamping positions as shown in Figs. 1 and 2. To provide a camming action to increase the clamping pressure of the hanger on the garment, the locking end 10 of the lever 11 has an inclined or beveled surface 13 to contact the upper end of the member 2 as shown herein.

The lever 11 is mounted on the member 1 with its locking end 10, when in locking position, disposed between the side edges of the members as shown in full lines in Fig. 1. This protects the locking end 10 of the lever 11 from being struck

by exterior objects and raised out of locking position in applying the hook portion 14 of the hanger to and removing it from a hanger support. The outer end 15 of the lever 11 is its actuating end and extends beyond a side of the hanger for accessibility at all times.

The rigid portion 7 of the hanger member 1 extends to a greater extent beyond the hinge means than the other rigid portion 8 and terminates in the hook element 14 which is integral and coplanar with the rest of the member 1. The hook element 14 opens to one side of the hanger as shown.

The modification shown in Figs. 5 and 6 provides for a wider spread for the hanger members 1a, 2a and employs a locking lever 16 not as wide as the space between the members 1a, 2a above the hinge means which connects them. Also, the hinge means is slightly different structurally than the one shown in the previous figures.

The hinge means shown in Figs. 5 and 6 comprises screw eyes 17, 17 screwed into the respective members 1a, 2a and engaged by a hinge pin 18 held in place by a small nail 19 driven in one of the hanger members and fitted into a notch 20 in the pin as shown.

Mounted on the inner face of the hanger member 2a above the hinge is a tapered or wedge shaped block 21 which is engaged by the inner end 22 of the lever 16. The end of the lever at the block 21 is inclined or beveled to co-act with the block to tightly clamp the member 2a in closed position. A stop (not shown) may be provided on the member 1a to prevent the lever 16 when swung into its unlocking position from entering between the members 1a, 2a to hinder their movement into fully open positions.

The hanger devices shown and described are simple in construction and operation and may be inexpensively made. The hinge means in particular comprise few metal parts. The hanger designs are sturdy and strong and provide ample clamping pressure for holding a garment for hanging in a dependent position. In both forms shown, the locking members are above the shorter of the two garment clamping members so that the locking members when swung into unlocking positions will not hinder the hangers being opened to the fullest extent. This may be done by pressing inwardly on the shorter member above the hinge while holding the longer member which forms the body member of the device in both forms. With the locking member supported on the body member above the hinge, the locking member may be moved into unlocking position to release a garment from the hanger without removing it from its support.

The details of construction and arrangement of parts shown and described may be variously changed and modified without departing from the spirit and scope of my invention, except as pointed out in the annexed claims.

I claim as my invention:

1. A trouser hanger of the character described comprising, a pair of trouser clamping members, each having a body portion comprised of substantially coplanar, connected, jaw and upwardly extending rigid portions, hinge means hingedly connecting said members at their upwardly extending rigid portions for relative movement of the jaw portions towards and from each other for opening and closing the hanger, one of said members having its upwardly extending rigid portion extending above the corresponding portion of the other member and terminating in means for suspending the hanger from an overhead support, and locking means carried by the member provided with said hanger suspending means, said locking means being movably mounted on said last named member between its hanger suspending means and the upper end portion of the other member, said locking means being movable substantially parallel to the member mounting it and transversely to said hinge means into the space between the members and engageable with both members to lock the same in closed position, the locking means engaging the upper end portion of the shorter member above the hinge means.

hinge means hingedly connecting said members for relative movement towards and from each other for opening and closing the hanger, said hinge means consisting of screw eyes inserted into the members and a pin inserted through the same, a stop fixed to one of the members and engaging the pin in a notch therein for holding the pin in place, and a locking element mounted on one member and engageable with the other member for locking the same in closed or clamping position.

2. A garment hanger of the character described comprising, a pair of opposed garment clamping members, each having a body portion comprised of substantially coplanar, connected, jaw and upwardly extending rigid portions, hinge means hingedly connecting said members at their upwardly extending rigid portions for relative movement of the jaw portions towards and from each other for opening and closing the hanger, one of said members having its upwardly extending rigid portion extending above the corresponding portion of the other member and terminating in means for suspending the hanger from an overhead support, and locking means carried by the member provided with said hanger suspending means, said locking means being movably mounted on said last named member between its hanger suspending means and the upper end portion of the other member, said locking means being movable substantially parallel to the member mounting it and transversely to said hinge means into the space between the members and engageable with both members to lock the same in closed position, the locking means engaging the upper end portion of the shorter member above the hinge means.

3. A garment hanger of the character described comprising, a pair of opposed garment clamping members, each having a body portion comprised of substantially coplanar, connected, jaw and upwardly extending rigid portions, hinge means hingedly connecting said members at their upwardly extending rigid portions for relative movement of the jaw portions towards and from each other for opening and closing the hanger, one of the members having its upwardly extending rigid portion extending above the corresponding portion of the other member and terminating in a hook element for suspending the hanger from an overhead support, and a locking lever pivoted on the upwardly extending rigid portion of the member provided with the hook element between the latter and the upper end of the upwardly extending rigid portion of the other member, said locking lever having its locking end movable substantially parallel to the member mounting the lever and independently of and transversely to said hinge means into the space between the members and engageable with both members to lock the same in closed position, the locking lever engaging the upper end portion of the shorter member above the hinge means.

ROBERT H. WOLLIN.
